UNITED STATES PATENT OFFICE.

FLORENCE MADELINE PEART, OF LISCARD, ENGLAND.

FOUNTAIN AND STYLOGRAPHIC PEN.

1,302,842.

Specification of Letters Patent.

Patented May 6, 1919.

Application filed August 9, 1917. Serial No. 185,232.

To all whom it may concern:

Be it known that I, (Mrs.) FLORENCE MADELINE PEART, a subject of the King of England, residing at Grove House, Sea View Road, Liscard, in the county of Chester, England, no occupation, have invented certain new and useful Improvements in or Relating to Fountain and Stylographic Pens, of which the following is a specification.

This invention relates to fountain and stylographic pens of the "safety" type, that is, of the kind wherein the pen nib or stylus, as the case may be, is connected with a feed-bar or stem longitudinally arranged within the pen body or barrel, which nib or stylus is projected from or withdrawn into the barrel on the actuation of a rotary head piece arranged on the barrel top through the engagement of a lateral pin provided on said bar or stem in a helical slot formed in a surrounding tubular element which is revolved, to effect the reciprocation of said feed-bar or stem through its connection with said rotatable head piece.

The object of my invention is to provide a pen of the above character wherein the members are connected or articulated to prevent the shearing off of the rotary head piece of the pen, and fracture of the parts connected therewith or operated thereby.

I will further describe my invention with the aid of the accompanying sheet of explanatory drawings which illustrate one mode of embodying same.

In said drawings, Figure 1 is a longitudinal elevation, partly in section, of a "safety" reservoir pen provided with my improvements; and

Fig. 2 is an enlarged cross section of the pen, taken as on line A—A, Fig. 1.

a represents the main body or barrel section of a pen, and *b* a feed-bar longitudinally arranged therein, said feed-bar *b* being provided with a lateral pin or projection *c* adapted to move in a longitudinal guide recess *d* formed in the barrel wall when a

helically-slotted tube *e* is revolved, in the well known manner.

f indicates a head-piece which is secured by a pin *g* to a stem *h* on the lower end whereof said tube *e* is suitably secured, and *f*¹ is an inner extension of said head-piece *f* adapted to lie within a recess *i* provided in a barrel member *j* which latter is screwed by means of a reduced portion or neck *j*¹ to the main barrel section *a*. *k* represents a spiral groove or recess formed in said head-barrel section extension *f*¹ and *l* is a metal saddle piece adapted to fit in said spiral groove *k* and formed with a lug or projection *l*¹ which enters a vertical groove or slot *m* of the wall of said recess *i*.

It will be seen that when said head-piece *f* is turned to project or retract the pin nib *n*, said saddle *l* *l*¹ through its engagement in said wall slot *m* and said spiral groove *k* of the head extension *f*¹ travels vertically and constitutes a stop to limit the rotary motion of said head piece *f* and hence stops the longitudinal travel of said nib *n* when either of the solid end walls *o* or *p* of the head extension groove or slot *k* abuts against the saddle.

Having now described my invention, what I claim as new and desire to secure by Letters Patent is:—

1. In a fountain or stylographic pen, of the safety type, a pen body having a groove, a pen nib, a head piece adapted by rotation to adjust said pen nib, said head piece having a portion thereof provided with a spiral groove, and means limiting the rotary movement of said head piece, comprising a saddle piece disposed in the spiral groove of said head piece and projecting into the groove of said pen body.

2. A fountain or stylographic pen, comprising, in combination, a body, a feed bar in said body and to which a pen nib is attached, a rotatable head piece, a helically slotted tubular element, a stem connecting said head piece with said tubular element, a lateral pin provided on said feed bar engag-

ing in the helical slot of said tubular element and in a guide slot formed in said body, so that said head is projected or retracted through the rotation of said head piece and helically slotted tubular element, said head piece having an inner extension provided with a spiral groove, said pin body having a longitudinal groove in that portion thereof adjacent the extension of said

head piece, and a saddle piece disposed in 10 the spiral groove of said head piece and projecting into the groove of said pin body.

In testimony whereof I affix my signature in the presence of two witnesses.

FLORENCE MADELINE PEART.
